UNITED STATES PATENT OFFICE

VICTOR MAUCK, OF MERION, PENNSYLVANIA

GAS WATER HEATER

Original application filed November 24, 1924, Serial No. 752,037. Divided and this application filed November 22, 1927. Serial No. 235,025.

This is a division of my application Serial No. 752,037 filed November 24, 1924, wherein thermostatically controlled heaters, such as herein disclosed, are disclosed and novel features of construction and arrangement of the combustion chamber and its appurtenances are claimed.

My invention herein claimed relates to the burner and cooperative features of construction and arrangement of such a heater adapted to be included in a house water supply system and comprising a container which is a hot water reservoir, and means constructed and arranged to automatically regulate and maintain a predetermined temperature of the water stored in said reservoir, with the minimum consumption of gas.

The purpose and effect of my invention herein claimed is to provide a burner which 20 may be secluded from the atmosphere in the heater structure and is yet adapted to be readily removed, in slip connection with a gas supply conduit extending horizontally in the burner casing; to permit cleaning the 25 minute jet orifices of the burner and the surface of the water container immediately above the burner which become incrusted with products of combustion which are non-conductive of heat.

The form of heater hereinafter described 30 includes the combination with such a water reservoir, having a combustion chamber at the bottom thereof; of a burner in that chamber arranged to heat the water in said 35 reservoir; an automatically, thermostatically, operative valve controlling a gas conduit leading to said burner; whereby said burner is continually supplied with gas, but in a volume which is automatically varied in 40 accordance with the temperature of the water in said reservoir; a needle valve between said conduit and said burner, whereby the flow of gas to said burner may be adjustably varied independently of said thermostatically controlled valve; a heat insulating 45 covering for said container and combustion chamber, including a heat insulating closure for the bottom of said chamber; and means for removably securing said closure; whereby said chamber is substantially secluded

from the outer atmosphere, and the normally minute flames at the burner thus protected from any drafts which would extinguish them if exposed in an ordinary combustion chamber.

My invention includes the various novel features of construction and arrangement herein set forth. 55

In said drawings; Fig. I is a plan view of a gas water heater conveniently embodying 60 my invention.

Fig. II is an inverted plan view of said heater.

Fig. III is a fragmentary vertical sectional view of said heater, taken on the line 65 III, III in Fig. I.

Fig. IV is a fragmentary vertical sectional view of said burner and its appurtenances, including said needle valve.

Fig. V is a right hand side elevation of 70 the gas conduit and thermostatically operative valve, as shown in Fig. III.

Fig. VI is a detached plan view of the water spreader shown in Fig. III.

In said figures; the water reservoir container comprises the cylindrical metal shell 1, having the cold water inlet 2 and the hot water outlet 3 at the top thereof, and the combustion chamber 5 at the bottom thereof. The diaphragm 6 forms the bottom closure 75 of the water space 7 in said container 1, and the top of said combustion chamber. The flue 10 has its lower end connected with said diaphragm 6, and extends to the outer atmosphere, through said water container, parallel 80 with, but eccentric to, the axis of said container shell 1. 85

The hollow oblate water spreader 11 is mounted in eccentric relation with said diaphragm 6 and extending below the latter 90 in said combustion chamber; having at its upper portion, in coaxial relation, an externally screw threaded neck flange 13 extending in a corresponding opening surrounded by the flange 14 in said diaphragm 95 6. Said spreader has, in coaxial relation therewith, but eccentric to said container, the socket 15, engaged with the lower end of the hot water riser pipe 16 which terminates in spaced relation with the top of 100

said container shell 1. Said spreader also has two diametrically spaced cold water inlet nozzles 17, at respectively opposite sides of said socket 15 and in communication with the water space 7 through said spreader neck 13.

The water drain pipe 18 extends from the bottom of said spreader 11 to the exterior of said combustion chamber 5 where it is provided with the drain cock 19, through which sediment may be withdrawn from said spreader. The collar 20 encircles said drain pipe 18, and is provided with the set screw 21 to secure it in adjusted position. The gas burner includes the hollow horseshoe shaped body 23, having the radially extending cross bars 24 forming axial bearings 25 embracing said drain pipe 18 and resting upon said collar 20. The mixing tube 26 extends from said burner body 23 in eccentric tangential relation thereto but in diametrical relation with said container 1 and combustion chamber 5, as best shown in Fig. II, and is slip fitted over the gas supply tube 27. The arrangement is such that said burner may be readily withdrawn and replaced laterally with respect to said pipe 18 and collar 20 which support it. As shown in Figs. III and IV; said mixing tube 26 is enlarged at its outer end and provided with the restricted air inlet 28 at the bottom thereof.

As shown in Figs. II, III and V; the gas conduit 30 leading to said burner 23 has the automatically, thermostatically, operative valve 31, arranged to control it in accordance with the expansion and contraction of a thermostatic element in the tube 32, which is rigidly connected with said valve. Although any suitable form of said valve 31 may be employed; that indicated is a specific form disclosed and claimed in Letters Patent of the United States No. 1,542,573 granted to Arthur E. Paige, June 16, 1925.

Said tube 32 extends diametrically in the water space 7 in said container shell 1, between said flue 10 and hot water riser pipe 16, and said valve 31 and tube 32 are detachably connected with said container shell 1 by the screw thread on the valve casing engaging the spud 33 in said shell.

I also find it convenient to provide said gas supply conduit 30 with the manually operative stop cock 34, leading to said conduit 27, between said automatic valve 31 and said burner 23; and also to provide the manually operative needle valve 35 in said conduit 27 between said stop cock 34 and said burner 23 in cooperative relation with an inlet port in the nozzle 36 which is detachably connected with said conduit 27, in coaxial relation with said mixing tube 26.

It is to be understood that said stop cock 34 may be manually opened or closed, to either permit or prevent the passage of gas

through said automatically, thermostatically, controlled valve 31. The function of said valve 31 is to limit the minimum flow of gas to the burner 23, and vary the flow in accordance with the temperature of the water in the container 1, so as to normally maintain the water in the reservoir space 7 at a predetermined temperature for which said valve 31 is calibrated. At that temperature, the gas supplied to said burner is only sufficient to maintain extremely minute flames thereat; so that such flames are normally less than one eighth inch high and, consequently, very feeble and easily extinguishable by even a feeble draft upon them.

The function and effect of said needle valve 35 is to permit the operator to clean, and vary the effective area of, the port surrounding the inner, conical, end of said valve 35, leading through said nozzle 36 directly to the burner. Said valve 35 thus limits the maximum flow of gas to said burner.

The heater chosen for illustration is of the type wherein a considerable volume of hot water is stored and normally maintained at a predetermined temperature, say 170° F.; as distinguished from heaters which have a minimum storage capacity and depend for their efficiency upon rapid heating of a minimum quantity of water upon demand. Therefore, it is important to conserve all of the heat generated by combustion of the gas at said burner 23, so as to minimize the quantity required. Therefore, I provide the heat insulating casing for said container and combustion chamber, and including the exterior shell 38, in concentric spaced relation with said container shell 1, and a refractory porous lining 39 for the same, which may be conveniently formed of involutedly wrapped, primary plane, sheets of corrugated asbestos paper, which form a cylinder filling the space between said concentric cylindrical shells 1 and 38, as indicated in Fig. III.

Said heat insulating casing includes the metallic top cover 40 having the refractory lining 41 which may be conveniently formed of the same material as the lining 39. Said casing shell 38 is also provided with the base cover 42 having the opening 43 in coaxial relation with said water container shell 1; affording access to the combustion chamber 5 to permit the operator to adjust and clean said burner 23.

However, if the burner 23 remained thus exposed; a considerable volume and pressure of gas would be required to maintain the burner lighted; whereas, I find that the desired temperature of the stored water can be maintained by the combustion of gas at such a slow rate that it would be impossible to thereby continuously maintain the flames 44 at said burner, if the latter were exposed to any air draft. Therefore, I provide a

heat insulating closure for said opening 43, including the annular metal frame 45 containing the lining 46 of porous refractory material, conveniently such as above described. Said closure 45 is detachably connected with said base 42 by the clip 48 which is stationary upon said casing base 42, and the slide catch 49 which is mounted to reciprocate through the stationary bight 50 upon said casing cover 42, diametrically opposite to said clip 48. Said base 42 has flanged plates 52 welded thereon to detachably engage the legs 53, by their respective wedge lugs 54.

It may be observed that the construction and arrangement above described are such that the space in said combustion chamber 5 is substantially secluded from the outer atmosphere, by a porous medium excluding all direct air drafts from said flames 44 at the burner 23. The air necessary for combustion is let into said chamber 5, only through the minute pores of said lining 46 and interstices at the junctions of said closure 45 with said outer casing cover 42; so that the most minute flames 44 may be normally maintained upon said burner 23 in an atmosphere which is undisturbed by any air draft.

Said heater mechanism operates as follows: Said catch 49 being withdrawn and said bottom closure 45 removed to afford access to the combustion chamber 5; and said needle valve 35 retracted to determine the maximum flow of gas to the burner 23 through said nozzle 36; the gas is turned on by opening the stop cock 34 to the position shown in Figs. III, IV and V, and the gas ignited at the outlets in the top of said burner 23 to form the flames 44. The water being cold and said valve 31 wide open, said flames are large and strong. Thereupon, said closure 45 is replaced and secured as indicated in Fig. III and, by the operation of the thermostatic element 32, affected by changes in the temperature of the water in the container chamber 7; the supply of gas permitted to pass through said supply conduit 30 and the valve 34 and around the valve 35 to said burner 23 is gradually diminished to the minimum, in accordance with the rise of temperature of the water.

Owing to the oblate form of said spreader 11, the hot water rises within it to the top thereof and flows upwardly through the riser 16 into the upper part of said container chamber 7; displacing a corresponding volume of cold water which flows downwardly through said spreader neck 13 and nozzles 17 into contact with the hot lower wall of said spreader, thus circulating the water from said container 1 through said spreader until the desired temperature thereof is reached and maintained.

Of course, said valve 31 is operated by the thermostatic element in the tube 32, to gradually diminish the volume of gas supplied to the burner 23 in accordance with the rise in temperature of the water in said reservoir space 7, until the minimum is reached which will maintain the desired temperature of the stored water under normal conditions. The gas flames 44 remain continuously lighted at said burner 23 although varied in height in accordance with the volume of gas being consumed which, of course, depends upon the rate at which water is withdrawn from the reservoir space 7 with consequent lowering of the temperature thereof by the influx of cold water through the pipe 2. It may be observed that the latter terminates immediately above said thermostatic element 32 so that the latter is instantly affected by inflowing cold water, to instantaneously vary the supply of gas to said burner 23.

In order to remove said burner 23, through said opening 43 without removal of any of the pipe connections, it is only necessary to shift it to the left in Fig. III far enough to release the outer end of the mixing tube 26 from the gas supply tube 27. Said burner may then be partly turned around said drain pipe 18 and withdraw from the latter. Such removal is only rendered readily possible by the coordinate location, arrangement, and shape of the parts shown in Fig. II, to wit, the pipe 18 is in eccentric relation to the axis of the shell 1, the axis of the mixing tube 26 is in tangential relation to the arcuate body 23 of the burner; the gap in the perimeter of the latter is in oblique relation to the axis of said mixing tube; and the gas inlet conduit 27 is in radial relation to said shell 1.

Although I prefer to conserve the heat in the container and combustion chamber by means of metal members lined with porous refractory material, as described; any suitable heat insulating means may be employed.

It is the ordinary practice to provide gas water heaters with substantially large openings through which the outer atmosphere may freely communicate with the space in which combustion is affected; upon the theory that such provision for large volumes of inflowing air is essential for the proper operation of a gas burner. As far as I am aware, it is entirely novel and original with myself to seclude such a burner in a chamber from which the outer atmosphere is excluded as above described, regardless of whether such seclusion is attained by refractory means or not.

Moreover, it is the usual practice to provide the mixing tubes leading to gas burners with a series of air inlets encircling the gas inlet; upon the theory that such an arrangement is necessary or desirable to facilitate

tate the mixture of the air with the gas. However, the volume and rate of flow, and consequent pressure, of gas in my improved heater above described, to maintain the stored water at the predetermined temperature aforesaid, are so slight that it was found in practice that such air inlets permitted a considerable portion of the gas to drift, backward, out of the air inlets above the gas inlet and to thus escape, unconsumed, through the flue. Therefore, I found that hermetically sealing the upper portion of the mixing tube 26 and providing a restricted air inlet 28 only at the bottom thereof prevented such escape and waste of gas and caused all of the gas passed by the automatically thermostatically controlled valve to be delivered through the burner and consumed thereat. Although I have found it convenient to form said inlet 28 as a slot extending sectorially in said tube 26; of course, it may be otherwise shaped; the essential feature being that means are provided to hermetically close the mixing tube around the gas inlet, except for a restricted air inlet below the gas inlet, and it may be observed that said air inlet is at a greater distance from the jet orifices in the top of the burner than said gas inlet.

Therefore, I do not desire to limit myself to the precise details of construction and arrangement herein set forth, as it is obvious that various modifications may be made therein without departing from the essential features of my invention, as defined in the appended claims.

I claim:

1. In a gas water heater, the combination with cylindrical shell having a water container in the upper portion thereof, a combustion chamber in the lower portion thereof, and a restricted opening in the bottom of said shell in coaxial relation therewith; of a removable closure for said opening; a water drain pipe pending from said container through said combustion chamber and its closure, in eccentric relation with the axis of said shell; a burner support carried by said water pipe; a gas inlet conduit extending radially through the wall of said shell into said combustion chamber in tangential relation with said drain pipe; the portion of said gas conduit extending into said combustion chamber being smoothly cylindrical; and a gas burner comprising a horseshoe-shaped body having a gap in its perimeter and bearings extending inwardly upon opposite sides of said gap adapted to detachably embrace said pendent pipe and rest upon said support on said pipe, and having a mixing tube projecting from said body and fitted over said gas conduit; the axis of said mixing tube being in tangential relation with said body, and the gap in the perimeter of the latter being in oblique re-

lation to the axis of said mixing tube; whereby said burner is stably supported in level position solely by said pipe and gas conduit but is readily removable therefrom, alone, and through said opening, when said closure is removed.

2. In a gas water heater, the combination with a cylindrical shell having a water container in the upper portion thereof, a combustion chamber in the lower portion thereof, a restricted opening in the bottom of said shell in coaxial relation therewith, and a removable closure for said opening; of a water pipe pending from said container through said combination chamber and its closure; a burner support carried by said water pipe; a gas inlet conduit extending through the wall of said shell into said combustion chamber in tangential relation with said water pipe; the portion of said gas conduit extending into said combustion chamber being smooth; and a gas burner comprising an arcuate body having a gap in its perimeter and bearings extending inwardly upon opposite sides of said gap, adapted to detachably embrace said pendent pipe and rest upon said support on said pipe, and having a mixing tube projecting from said body and fitted over said gas conduit; the axis of said mixing tube being in eccentric relation with said body, and the gap in the perimeter of the latter being in oblique relation to the axis of said mixing tube; whereby said burner is stably supported in level position solely by said pipe and gas conduit but is readily removable therefrom, alone, and through said opening when said closure is removed.

In testimony whereof, I have hereunto signed my name at Conshohocken, Pennsylvania, this Seventeenth day of November, 1927.

VICTOR MAUCK.
